(57) **CLAIM**

The ornamental design for an electric cooker, as shown and described.

DESCRIPTION

1. Electric cooker:

1.1: Figure 1.1 illustrates a perspective view of an electric cooker of the present invention;

1.2: Figure 1.2 illustrates a front view of the electric cooker shown in Figure 1.1;

1.3: Figure 1.3 illustrates a rear view of the electric cooker shown in Figure 1.1;

1.4: Figure 1.4 illustrates a left side view of the electric cooker shown in Figure 1.1;

1.5: Figure 1.5 illustrates a right side view of the electric cooker shown in Figure 1.1;

1.6: Figure 1.6 illustrates a top view of the electric cooker shown in Figure 1.1; and,

1.7: Figure 1.7 illustrates a bottom view of the electric cooker shown in Figure 1.1.

Figures/Reproductions 1.1 through 1.7 illustrate an electric cooker. Broken line portions illustrated in the various views of the present invention, form no part of the claimed design.

1 Claim, 7 Drawing Sheets
